HOLDER FOR A CARAFE OR THE LIKE

Kurt E. Christoffersen, Gales Ferry, Conn., assignor to
The Artistic Wire Products Co. of Conn., Incorporated,
Norwich, Conn., a corporation of Connecticut

Filed Nov. 15, 1960, Ser. No. 62,853

Term of patent 14 years

(Cl. D58—26)

FIG. 1

FIG. 2

FIG. 4

Fig. 1 is a rear perspective view of a holder for a carafe or the like embodying my new design.

Fig. 2 is a top plan view thereof.

Fig. 3 is a side elevational view thereof.

Fig. 4 is a front elevational view thereof.

The side of the device not shown is substantially like the side shown in Figs. 1 and 3.

The portions shown in broken lines are for illustrative purposes only.

I claim:

The ornamental design for a holder for a carafe or the like, substantially as shown and described.
